UNITED STATES PATENT OFFICE.

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF VIRGINIA.

FESTOONING MACHINE.

Application filed November 11, 1922. Serial No. 600,262.

To all whom it may concern:

Be it known that I, FRANK A. BROWNE, a citizen of the United States, residing at Wayne, county of Delaware, and State of Pennsylvania, have invented certain new and useful Improvements in Festooning Machines, whereof the following is a specification, reference being had to the accompanying drawings.

10 This invention relates to the manufacture or treatment of fabrics and web materials, and its object it to provide an improved festooning device for the purpose of draping the material into contiguous loops which are progressed and the material subjected in the interim to any desired treatment, the essential feature of the present invention consisting in the provision of means for forming a maximum number of loops within 15 given horizontal confines so as to economize in the utilization of floor space. The above object is accomplished in accordance with the present invention by progressing the looped web in a direction which is inclined 20 with respect to the horizontal, while the material is suspended perpendicularly, and in order that the height of the machine may not be unduly prolonged I prefer to direct the loop supporting means in a sinuous path 25 so as to obtain the desired result while at the same time progressing the material in a general horizontal direction.

These and other objects are accomplished by what I now regard as the preferred embodiment of my invention from among other possible forms and arrangements embraced within the spirit of the invention and the scope of the appended claims.

In the accompanying drawings Fig. I is a 40 view in side elevation of a festooning machine constructed in accordance with my invention and illustrating the same somewhat diagrammatically.

Fig. II is a view of the machine in end 45 elevation.

With reference to the drawings 10—10 indicate a pair of vertical frame members of standardized material or otherwise constructed in any manner found suitable or 50 convenient and disposed in horizontal spaced relation to form an enclosure within which to support and contain the festooning arrangement. The latter consists of two pairs of upper sprocket wheels 11 and 12 located 55 at the entering and leaving sides of the

machine, and vertically aligned pairs of lower sprocket wheels 13 and 14 located respectively beneath the sprocket wheels 11 and 12, said pairs of sprockets constituting a rectangular arrangement over which a 60 pair of endless chains 15 are passed to traverse rectangular paths which are continuous throughout.

Located adjacent the sprockets 11 are a 65 pair of sprocket wheels 16 in transverse alignment, and located between said sprockets 16 and the aforesaid sprockets 12 are other pairs of transversely aligned sprocket wheels 17, arranged in alternate varying elevations so as to cause the chains passing 70 between the sprockets 16 and 12 to traverse a sinuous path. The chains 15 are for the purpose of supporting festooning bars 18 in horizontal positions and uniformly spaced 75 relation, said festoon bars being fastened to the chains by means of attachment links in the chains in a manner well known in the art.

In order that the space within the machine 80 may be free to permit passage of the loops I prefer to mount the sprocket wheels, particularly the upper sprocket wheels upon shafts 19 which are supported upon lateral extensions 20 of the frame members 10, each shaft being preferably provided with a two bearing support to insure stability and maintenance of the relation of the several parts, the bearings being indicated at 21.

Any suitable means found convenient may 85 be utilized to cause motion of the chains carrying the festooning bars and hence I have not disclosed any specific driving means.

The material is fed between rollers 22 90 constituting part of a feeding means indicated generally at 23 and located at the upper portion of the machine for the purpose of directing the web material downwardly at a point between the sprockets 11 and 16, so that the act of progressing the festooning bars will cause the latter to successively engage the web. By feeding the web either constantly or intermittently the latter is caused to drape between adjacent 100 pairs of festoon bars to form the loops 24 through the medium of a pivoted draping element 16' in a manner well known in the art. It will be noted that as the festoon bars 105 traverse an inclined path between the 110

sprockets 16 and 17 or between an adjacent pair of sprockets 17 the plies of material forming the loops are brought closely together.

5. In this manner a greater number of loops may be formed and retained within a given horizontal distance than in machines heretofore employed in which the festoon bars were traversed in a horizontal plane. It 10 will be apparent that this result is obtained by reason of the inclined direction of travel of the loop supporting bars and hence compactness may be accomplished by continuing the course of travel in an inclined unbroken 15 path, but in order that the material may be progressed at the same time in a substantially horizontal direction and the height of the machine maintained within bounds I prefer to divert the course of travel of the bars to 20 describe a substantially sinuous path which accomplishes the same results. It will be noted that in passing around the sprockets the festoon bars cause the loops to alternately widen and narrow, while the pitch or 25 spacing of the bars remains invariable. The movement of the plies thus induced also acts to cause air circulation around the material to hasten drying. By reason of the rotating movement of the festoon bars caused by 30 their movement in a circuitous path the material gradually creeps around so as to prevent the formation of a permanent curvature therein by reason of its flexure around the bars.
- 35 Having thus described my invention, I claim:
1. In a festooning machine, means traversing a varyingly inclined path for suspending material in festoons to compact 40 the number of the ply intervals within given confines.
2. In a festooning machine, means for draping and progressing material in festoons, and means for directing travel of the 45 aforesaid means along a path varyingly inclined with respect to the horizontal to compact the width of the ply intervals within given confines.
3. In a festooning machine, means for 50 draping material including festoon bars, and means for progressing the festoon bars along a path inclined with respect to the horizontal whereby the width and interval of the material loops are constantly varying.
- 55 4. In a festooning machine, means for

draping and supporting the material, and means for progressing the supporting means through the machine along a path alternatingly inclined with respect to the horizontal 60 to compact the width of the ply intervals.

5. In a festooning machine, means for draping and supporting the material, and means for progressing the supporting means along a sinuous path to continuously vary 65 the width of the ply intervals during progression along said sinuous path.

6. In a festooning machine, endless elements, festoon bars supported thereby, and means over which the endless elements are 70 trained with varying elevation to direct travel of the bars along a path inclined with respect to the horizontal.

7. In a festooning machine, endless elements, festoon bars supported thereby, 75 sprocket wheels around which the chains are trained, said sprockets being so arranged as to direct the chains to traverse a sinuous path, and means for draping the material over the festoon bars whereby the material 80 loops and plies are closely spaced.

8. In a festooning machine, endless elements, festoon bars supported thereby, sprocket wheels over which the chains are 85 trained to cause the latter to traverse a circuitous path when driven, and other sprocket wheels over which the chains are passed causing the latter to traverse a sinuous path, and means for draping the material 90 over the bars.

9. In a festooning machine, means traversing an undulatory path for suspending material in loops to vary the ply intervals while passing through the machine.

10. In a festooning machine, means 95 adapted to traverse a sinuous path for suspending material in loops whereby said material loops are caused to alternately approach and recede from one another during 100 progression through the machine.

11. In a festooning machine, the combination of loop carrying bars having uniform spaced relation, and means whereby said bars are caused to traverse an undulatory path through the machine to effect alternate approach and recession of the material loops during progression through the machine.

In testimony whereof, I have hereunto signed my name at Philadelphia, Pennsylvania, this 9th day of November, 1922.

FRANK A. BROWNE.
